UNITED STATES PATENT OFFICE

106,800

DESIGN FOR A PIPE HOLDER

Esther A. S. Langslow, New York, N. Y.

Application March 15, 1937, Serial No. 68,171

Term of patent 7 years

To all whom it may concern:

Be it known that I, Esther A. S. Langslow, a citizen of the United States, residing at New York, in the county of New York and State of New York, have invented a new, original, and ornamental Design for a Pipe Holder, of which the following is a specification, reference being made to accompanying drawing, forming part thereof.

I claim:

The ornamental design for a pipe holder, as shown.

ESTHER A. S. LANGSLOW.
